ELMER L. KNOEDLER, OF GLOUCESTER CITY, NEW JERSEY, ASSIGNOR TO WELSBACH LIGHT COMPANY, OF GLOUCESTER CITY, NEW JERSEY, A CORPORATION OF NEW JERSEY.

MANTLE FOR INVERTED INCANDESCENT GAS-LAMPS AND METHOD OF TYING THE SAME.

1,104,515.

Specification of Letters Patent. Patented July 21, 1914.

Original application filed February 17, 1911, Serial No. 609,194. Divided and this application filed February 24, 1913. Serial No. 750,053.

To all whom it may concern:

Be it known that I, ELMER L. KNOEDLER, a citizen of the United States, and resident of Gloucester City, county of Camden, State 5 of New Jersey, have invented a new and useful Improvement in Mantles for Inverted Incandescent Gas-Lamps and Methods of Tying the Same, of which the following is a full, clear, and exact description, reference 10 being had to the accompanying drawings, in which—

Figure 1 is a side elevation of a mantle secured to the supporting ring, showing the manner of tying the mantle on the ring; Fig. 15 2 is a perspective view of the doubled loop employed in the string; and Fig. 3 is a side elevation of the finished mantle after it has been turned.

My invention relates to mantles for inverted incandescent gas lamps and is designed to provide an improved inverted mantle having the securing cord entirely hidden within the fold of the mantle while, at the same time, improper drawing of the 25 mantle around the ring is avoided.

To that end the invention consists in such a completely hidden cord having a double loop with a knot also located within the fold.

30 It further consists in a tying cord having a single knot hidden in the fold.

It further consists in the method of applying and tying the cord.

The precise nature of my invention will 35 be best understood by reference to the accompanying drawings, which will now be described, it being premised, however, that various changes may be made in the details of construction of the mantle and supporting ring without departing from the spirit 40 and scope of my invention as defined in the appended claims.

Referring to the accompanying drawings, the numeral 2 designates the mantle, 3 the 45 supporting ring, and 4 the cord for securing the mantle to the ring.

The mantle blank is first placed in position around the supporting ring, the ring and mantle being supported in any desired 50 manner. I then place the tying cord around the ring and mantle with two loops, as

shown in Figs. 1 and 2. These loops are drawn tight and as they are drawn by the knot at one side, one loop will tend to draw the mantle in one direction, while the other 55 loop will tend to draw the mantle in the other direction, and both of said loops will clamp the mantle so that the drawing of the mantle by one loop will be prevented by the other loop. It is therefore evident that by 60 using two loops, the sidewise draw on the mantle is prevented so that there is no tendency to pull the mantle around the ring toward the knot. If a single loop is used, as the knot is drawn tight the mantle fabric 65 is drawn around toward the knot by the movement of the loop and the mantle fabric must then be pulled back and equalized by the operator. The double loop formation does away with this difficulty and prevents 70 drawing the mantle around the ring. After the knot has been tied, the mantle is turned back and finished in the usual manner.

The advantages of my invention result 75 from the double looped cord employed in tying the mantle to the ring, the holding action of one loop preventing the draw of the mantle by the other loop so that all portions of the mantle in engagement with the ring will be under about the same tension, 80 the loops being hidden within the mantle fold. They further result from the use of a single knot which is made possible by the two loops, this knot being hidden in the mantle fold.

85 This application is a division of my application Serial No. 609,194, filed February 17, 1911.

I claim:

1. An inverted incandescent mantle structure, comprising a mantle body and a supporting ring, said body having a circumferential fold at the ring secured by a plurality of cord loops having a knot, said loops and knot being hidden in the fold of the 95 mantle body between the two plies thereof; substantially as described.

2. An inverted incandescent mantle structure, comprising a mantle body and a supporting ring, having a circumferential fold 100 around the ring secured by a single knot, the cord and knot being hidden in the fold

between the two plies of the mantle body; substantially as described.

3. An inverted incandescent mantle structure, comprising a mantle body and a supporting ring, the mantle body having a circumferential fold at the ring secured by a plurality of cord loops having a single knot, the loops and knot being hidden within the fabric and lying between the two plies thereof around the ring; substantially as described.

4. The method of tying an incandescent mantle structure, consisting in assembling a mantle body open at both ends and a supporting ring within one end of the body, throwing a plurality of cord loops around the body and ring; knotting the same, and then turning the mantle inside out and clos-

ing the open end thereof opposite the ring end; substantially as described.

5. The method of tying an incandescent mantle structure, consisting in assembling a mantle body open at both ends and a supporting ring within one end of the body, throwing a plurality of cord loops around the body and ring, securing the ends of one of the loops by a single knot, turning the mantle inside out, and closing the open end opposite the ring end; substantially as described.

In testimony whereof, I have hereunto set my hand.

ELMER L. KNOEDLER.
